Primary Examiner — Eric Goodman*Assistant Examiner* — Amy Wierenga(74) *Attorney, Agent, or Firm* — Henry J. Cittone; Cittone & Chinta LLP(57) **CLAIM**

The ornamental design for a padded leg compression sleeve, as shown and described.

DESCRIPTION

FIG. 1 is a perspective view from above of a padded leg compression sleeve, showing my new design; and

FIG. 2 is front view thereof;

FIG. 3 is a back view thereof;

FIG. 4 is a side view thereof;

FIG. 5 is a side view thereof;

FIG. 6 is a top view thereof;

FIG. 7 is a bottom view thereof; and,

FIG. 8 is a perspective view from the side thereof.

The broken line illustration of environmental and other structures in the drawings are not part of the design sought to be patented.
